DESIGN FOR A CASING FOR A FUEL PUMPING UNIT

Herbert E. Kempton, Chicago, Ill., assignor to
Tuthill Pump Company, Chicago, Ill., a corpora-
tion of Illinois

Application February 28, 1935, Serial No. 55,651

Term of patent 14 years

To all whom it may concern:

Be it known that I, Herbert E. Kempton, a citizen of the United States, residing at Chicago, in the county of Cook and State of Illinois, have invented a new, original, and ornamental Design for a Casing for a Fuel Pumping Unit, of which the following is a specification, reference being had to the accompanying drawings, forming a part thereof.

In the drawings: Figs. 1 and 2 are perspective

views of a casing for a fuel pumping unit, showing my new design. Fig. 3 is a perspective viewed partly from the bottom of the casing. Fig. 4 is a plan view of said casing.

I claim:

The ornamental design for a casing for a fuel pumping unit, substantially as shown.

Signed at Chicago, Illinois, this 25th day of February, A. D. 1935.

HERBERT E. KEMPTON.
